ROBERT C. COLE, OF HARTFORD, CONNECTICUT, ASSIGNOR TO THE JOHNS-PRATT COMPANY, OF HARTFORD, CONNECTICUT, A STATUTE CORPORATION OF CONNECTICUT.

INCLOSED FUSE.

1,400,661.

Specification of Letters Patent. Patented Dec. 20, 1921.

Application filed April 2, 1920. Serial No. 370,637.

To all whom it may concern:

Be it known that I, ROBERT C. COLE, citizen of the United States, residing at Hartford, in the county of Hartford and 5 State of Connecticut, have invented a new and useful Improvement in Inclosed Fuses, of which the following is a specification.

This invention relates to renewable inclosed electric fuses of the knife blade contact type cartridge class and metal to metal closure species.

These devices are provided to protect apparatus connected in, and substances adjacent to the circuits. To effect protection the 15 fusible elements must open the circuits under exact predetermined conditions of overload and short circuit without endangering surrounding objects or injury to the permanent elements of the fuses. To insure

20 functioning as safety devices under all conditions the practical and commercial requirements as to dimensions, strength, carrying capacity, temperature rise, time of safe carrying of excess currents and opening of

25 the fusible conductor when the factor of safety is exceeded, and internal pressure and expulsion of gas when the renewable elements fuse, are exacting. These necessitate careful selection and relations of the materials forming the permanent and fusible

30 elements and also such provision for the relief of internal pressure resulting from the transformation of the fusible metal from solid to gas as will eliminate explosion, or

35 burning of the parts, or expulsion of dangerous flame. If no vent or an inadequate escape is provided for the gas pressure the permanent elements are liable to be irreparably damaged when the fusible element

40 melts. If the vent is too free, flames dangerous to surrounding objects are projected and there is also liability of injury to permanent parts of the fuses.

The amount of metal fused, however, is 45 considerably reduced if there is sufficient internal pressure to suppress the arc occurring at the time of fusing. Ideal action results when the elements are so constructed and related and the vents for the gas are so

50 proportioned that only sufficient internal pressure accrues to suppress the arc, for then but a minimum amount of metal is vaporized. This is best effected by designing the gas paths so that the gas generated 55 is conducted through tortuous passages, the

sizes of which can be definitely fixed, over and about large areas of a substantial amount of metal and permitted to escape through slight apertures which in the aggregate have relatively large cross-sectional 60 areas, so that the gas is quite free to escape but by the time it reaches the outer air is chilled below the danger point. This enables all capacities of fuses of this character to be manufactured in large quantities with 65 in the prescribed standard limits and sufficiently durable to resist all of the destructive factors and yet operate according to the most exacting requirements.

The object of this invention is to construct 70 a safety device of the class and type mentioned which will attain the above specified ends.

Figure 1 of the accompanying drawings shows a side view of a knife blade cartridge 75 fuse with a portion of the casing cut away to show the fusible conductor which is of the character of the well known "drop-out" link. Fig. 2 shows a section of one end of the casing of the fuse and the connected 80 parts. Fig. 3 shows a similar section of the same parts rotated ninety degrees. Fig. 4 shows an end view of the fuse. Fig. 5 shows an end view with the cap removed. Fig. 6 shows an end view with the cap and 85 cap plate removed. Fig. 7 shows an end view with the cap, cap plate and locking plates removed. Fig. 8 is a view looking at one side of one of the locking plates. Fig. 9 is a view looking at the other side of the locking 90 plate. Fig. 10 shows an edge view of a locking plate. Fig. 11 shows a side view of one of the knife blade terminals with the baffle plate in section.

The casing 1 of the embodiment of the invention illustrated is a tubular piece of the usual insulating material. Screwed into or otherwise secured in each end of the casing shown is a metallic ferrule 2 that has an exterior thread on its outer end. Each terminal, usually of copper, has an outer blade 3 for engagement with the spring plates of the common circuit terminals and an integral inner lug 4 to which an end of the element 5 of ordinary fusible metal is secured by bolt 6. The fusible link has two reduced sections 7 so that it will fuse first at these localities. While this type of link is preferred it is not an essential feature of the invention.

Secured tightly on each terminal is a circular baffle plate 8 which is but slightly smaller in diameter than the interior diameter of the ferrule in which it is located. 5 The baffle plate is fitted to the terminal so tightly that no gas can pass through the joint between the terminal and baffle plate, but it fits in the ferrule loosely so that there is a slight opening between its outer edge 10 and the interior wall of the ferrule through which gas can pass. In the outer edge of each ferrule, on diametrically opposite sides, are slots 9, and in the edges of the terminal and formed in part by the terminal and in 15 part by the outer face of the baffle plate are notches 10. Semi-circular key plates 11 with slots 12 shaped to fit into and about the notches in the edges of the terminal blade are slipped onto each blade from opposite 20 sides until they meet and form a circular disk that fits closely and substantially gas tight to the inner end of the blade of the terminal and against the outer face of the baffle plate and end of the ferrule. These 25 key plates are provided with pins 13 that extend inward when the key plates are in locking position and enter the notches in the end of the ferrule. The key plates are provided on one face with grooves 14 that 30 lead from the outer circular edge inward to the edges of the slots that fit the terminal blade. The number and size of these grooves can be proportioned to permit just the correct amount of gas to escape through 35 them. Fitted loosely on each terminal blade outside the locking plates is a circular metal cap plate 15, and screwed onto each ferrule is a cap 16 which at its outer edge has a flange 17 that when the cap is screwed 40 tightly on the ferrule causes the cap plate to press the locking plates tightly against the end of the ferrule. With the parts thus secured the locking plates prevent the rotation of and also any endwise movement of 45 the terminals. The outer face of the cap plate fits closely against the inner face of the flange on the cap so that there can be no leakage of gas between these surfaces, and the diameter of the locking plates when 50 put together is slightly less than the interior diameter of the cap.

To assemble the fuse the terminals provided with the baffle plates and connected by the fusible element are inserted into the casing with the baffle plates lying just inside of the ends of the ferrules which they loosely fit. The locking plates are then inserted 55 into the notches between the inner ends of the blades and the baffle plates with the pins 60 projecting into the slots in the ends of the ferrules. The cap plates are then slipped on the blades and finally the caps are placed over the cap plates and locking plates and screwed onto the ferrules. 65 When gas pressure is generated in the

interior of such a fuse, as a result of the vaporization of some of the metal of the fusible element, the pressure is relieved by the escape of gas outward past the outer edges of the baffle plates, through the slots 70 in the ends of the ferrules, then around the outer edges of the locking plates to the grooves in the faces of the locking plates and from thence to the atmosphere through the thin openings between the walls of the 75 slots in the cap plates and the surfaces of the blades.

These passages for the escape of gas and relief of internal pressure are free and yet small (being shown exaggerated in the 80 drawings) and tortuous. They conduct the gas outward a long distance over a considerable area of a substantial mass of metal and then let it escape through the spaces between the cap plates and the blades, which spaces 85 while very thin have a total cross-sectional area, which provides a sufficient yet widely distributed vent for the gas. While traversing these tortuous passages the hot gas is exposed to the cooling and condensing effect 90 of a considerable amount of cold metal and is chilled and condensed before it reaches the outer atmosphere to a degree far below that which is dangerous to objects in the vicinity. With these tortuous, yet free 95 paths, a fixed relatively low pressure can be obtained for a sufficient interval of time to accelerate the breaking down of the softened metal of the fusible element so that, particularly with the "drop-out" type 100 of link, but a small amount of metal is fused, and consequently the internal pressure is never abnormally high, for of course the smaller the amount of metal vaporized the less the internal pressure.

The details of construction of this safety device may be changed, as apparent to those skilled in this art, without departing from the invention.

The invention claimed is:

1. A fuse having an insulating casing, a metallic ferrule secured in one end of the casing, a cap screwed on the ferrule, a terminal extending through the ferrule and cap, a cap plate loosely fitting the terminal within the cap, a baffle plate secured tightly to the terminal within the end of the ferrule, detachable locking plates resting against the end of the ferrule between the cap plate and baffle plate and closely fitting the terminal and loosely fitting the cap, and means permitting the passage of gas from the interior to the exterior of the fuse about the edge of the baffle plate, around the edges of the locking plates, between the locking plates and cap plate, and out between the cap plate and terminal.

2. A fuse having an insulating casing, a metallic ferrule secured in one end of the casing, a cap screwed on the ferrule, a termi-

- nal extending through the ferrule and cap, a cap plate within the cap loosely fitting the terminal and closely fitting the cap, a baffle plate secured tightly to the terminal and loosely fitting within the end of the ferrule, and detachable semi-circular locking plates resting against the end of the ferrule between the 35 cap plate and baffle plate, said locking plates closely fitting and holding the terminal from rotary and longitudinal movements and loosely fitting the cap, with gas channels formed between the locking plates and the 40 cap plate from their outer edges to the terminal.
3. A fuse having an insulating casing, a metallic ferrule secured in one end of the casing, a cap screwed on the ferrule, a terminal extending through the ferrule and cap, a cap plate loosely fitting the terminal within the cap, a baffle plate secured tightly to the terminal within the end of the ferrule, 45 and detachable semi-circular locking plates resting against the end of the ferrule between the cap plate and baffle plate, said locking plates closely fitting the terminal and loosely fitting within the cap, a baffle plate secured tightly to the terminal and loosely fitting within the end of the ferrule, detachable semi-circular locking plates with pins extending into the slots in the ferrule, located between the cap plate and baffle plate, said locking plates closely fitting and holding the terminal from rotary 50 and longitudinal movements, and loosely fitting the cap, with gas channels formed between the locking plates and the cap plate from their outer edges to the terminal.
4. A fuse having an insulating casing, a metallic ferrule secured in one end of the casing, a cap screwed on the ferrule, a terminal extending through the ferrule and cap, 55 a cap plate loosely fitting the terminal and
